CLAIM

The ornamental design for a packaging for food products, as shown and described.

DESCRIPTION

FIG. 1 is a front, perspective view of a packaging for food products showing the claimed design;

FIG. 2 is a front view of the design of FIG. 1, where the back view is a mirror image of the front view of FIG. 2;

FIG. 3 is a right side view of the design of FIG. 1, where the left side view is a mirror image of the right side view of FIG. 3;

FIG. 4 is a top view of the design of FIG. 1; and,
FIG. 5 is a bottom view of the design of FIG. 1.

The broken lines are included for purposes of illustrating environment and form no part of the claimed design.
